UNITED STATES PATENT OFFICE.

MICHAEL LIPTAK, OF ST. PAUL, MINNESOTA.

FURNACE WALL.

Application filed October 30, 1925. Serial No. 65,767.

My present invention relates to furnace walls and provides a highly important improvement in the type wherein a single replaceable wall is anchored to outside vertical columns or metallic "buckstays". Generally stated, the invention consists of the novel devices, combinations of devices and arrangement of parts hereinafter described and defined in the claims.

10 A wall of this character will preferably be built up entirely of fire brick, although if the wall be made of sufficient thickness, some common bricks may be incorporated in the outer portion thereof. The wall, however, is 15 a single wall that may be replaced either in part or as an entirety.

In the accompanying drawings, which illustrate the invention, like characters indicate like parts throughout the several views.

20 Referring to the drawings:

Fig. 1 is a fragmentary perspective showing a furnace wall designed in accordance with my invention, some parts thereof being removed and some being broken away;

25 Fig. 2 is a fragmentary plan view showing one of the buckstays and a portion of the wall anchored thereto;

Fig. 3 is a section taken on the line 3—3 of Fig. 2;

30 Figs. 4 and 5 are perspective views showing certain of the specially constructed blocks of the wall illustrated in Figs. 1, 2 and 3;

Fig. 6 is a perspective showing one of the metallic block anchors;

35 Fig. 7 is a view corresponding to Fig. 1, but illustrating a slightly modified construction of the wall; and

Fig. 8 is a perspective showing one of the specially constructed blocks used in the structure illustrated in Fig. 7.

Describing first the structure illustrated in Figs. 1 to 6, inclusive, the numeral 9 indicates the vertical buckstays, which, as shown, are in the form of upright rolled steel beams. The numeral 10 indicates a metallic casing shown as applied to the exteriors of the buckstays 9.

The refractory wall is made up of horizontal belts of fire brick and interposed horizontal rows of sill blocks or tiles, the latter of which are anchored to horizontal ledge plates, which latter are interlocked to the buckstays. The horizontal belts of brick-work, in this structure, are shown as made up of bricks 11 laid as headers and bricks 12 laid as stretchers. Between each of these

horizontal belts is laid a horizontal row of the sill blocks or tiles 13 and 14 that are preferably much larger than common bricks, in depth, width and length. 60

For anchoring the sill blocks 13 and 14 to the buckstays, there are provided horizontally extended ledge plates or bars 15, which, at their inner edges, have upturned lock flanges 16 and, at their outer edges, have 65 downturned lock flanges 17, which latter are seated between the inner faces of the buckstays and offset upwardly projected ends of anchor brackets 18 riveted or otherwise rigidly secured to the several buckstays. 70

The sill blocks 13 and 14 are laid on the ledge plates 15 with their inner half portions more or less projecting inward of said ledge plates. These blocks 13 and 14, on their under sides, are formed with grooves 19 75

that receive the upturned flanges 16 of the ledge plates. The blocks 13 that are laid adjacent to the buckstays are also formed in their upper faces with longitudinal lock grooves 20 and with transverse lock grooves 80

21 that are adapted to receive the T-shaped inner ends 22 of flat metallic anchors 23, which latter are formed with hook-like outer ends 24. When these anchors are applied in the grooves 20—21, as shown in Fig. 2, with 85

their hook-like ends 24 engaged with the flanges of adjacent buckstays, it is evident that the said blocks 13 will be securely anchored to the buckstays both at their top and bottom portions and, hence, will be held 90

in horizontal positions even if some or all of the bricks of an underlying belt may be removed. The intermediate blocks 14, while not as securely anchored as the blocks 13 against tilting movements, are, nevertheless, 95

locked to the ledge plates against horizontal shifting movements, and when engaged by an overlying belt of bricks that form a bridge between the spaced blocks 13, said intermediate blocks 14 will also be prevented 100

from tilting, even when bricks of an underlying belt are removed. Moreover, it will be noted that one-half or more of the weight of the blocks 14 is on the ledge plates, so that there is little, if any, tendency for the 105 same to tilt.

By the means described, the brick wall is held in perfect alignment and anchored to the buckstays and thus securely held against tilting or lateral shifting movements. The 110 ledge plates 15 are preferably placed with their abutting ends lapped with the inner

flanges of the buckstays and with the anchor brackets 18.

In the wall illustrated in Figs. 1, 2 and 3, the blocks 13 and 14 do not extend in the wall to the inner or fire-exposed surface thereof and, hence, the spaces between the belts of brick 11—12 that would otherwise be left are filled in with fire bricks 25.

In some instances, the grooves 21 of the blocks 13 will primarily be formed therein at the place of manufacture, but in other instances, they will be omitted, and in which case the bricklayer may readily gouge out or cut the said grooves at the place found necessary to bring the anchors 23 in proper position for engagement with the buckstays. This gouging out of the grooves 21 would be necessary in some cases and especially where the spacing of the buckstays is not in accordance with a standard that is predetermined or known.

The wall illustrated in Fig. 7 is much like that illustrated in Figs. 1, 2 and 3. The lower portion thereof is of the identical construction except that in one horizontal row, the sill blocks 13' and 14' are extended through to the inner face of the wall. In this wall, the lower portion is much thicker than the upper portion and, hence, on the upper belt of bricks 11—12, there is placed a layer of beveled wall-reducing sill blocks 26. That portion of the wall above the sill blocks 26 is shown as made up of belts of fire brick 27 laid as headers and an interposed horizontal row of sill blocks 13^a and 14^a. The blocks 13^a and 14^a are like the blocks 13 and 14 of the wall illustrated in Figs. 1, 2 and 3, except that, as shown, they are provided at their adjacent edges with interlocking joints 28. The blocks 13^a are anchored to the buckstays by the metallic anchors 23 in the same manner as are the blocks 13. From statements made, it of course follows that the blocks 13^a and 14^a are grooved and interlocked to the ledge plates the same as before described in connection with the blocks 13.

It should be noted that the ledge plates 15 are detachably interlocked to the buckstays so that they may be readily replaced, section by section, if damaged or warped by the heat. Of course, when blocks are placed on the ledge plates, they will be positively and firmly anchored to the buckstays and blocks that normally rest thereon must be removed before they can be detached from the buckstays.

In the wall structures described, it is evident that all of the brickwork or masonry of the wall may be very readily replaced and that any part of any one belt may be removed without disturbing adjacent upper and lower belts, and, moreover, that the sill blocks themselves may be very readily replaced. Of course, the sill blocks them-

selves can be replaced only when the bricks of an immediately overlying belt have been removed, but the sill blocks above and the brick belt above the latter need not be disturbed in the replacement of said lower sill blocks. It also follows from statements made that the invention described is capable of any other modifications within the scope of the invention as herein disclosed and claimed. 75

What I claim is:

1. In a wall structure, metallic buckstays, having anchor brackets, plates connecting and interlocked with the brackets, sill blocks supported upon said plates in horizontal vertically spaced rows, and belts of brick-work between the horizontal rows of sill blocks. 80

2. In a wall structure, metallic buckstays, having anchor brackets, plates connecting with the brackets, sill blocks supported upon said plates and interlocked therewith, and arranged in horizontal vertically spaced rows and belts of brick-work between the horizontal rows of sill blocks, the said sill blocks forming continuous horizontal rows. 85 90

3. In a wall structure, metallic buckstays having anchor brackets, plates connecting with the brackets, and sill blocks supported upon said plates in horizontal vertically spaced rows, and belts of brickwork between the horizontal rows of sill blocks, the said sill blocks forming continuous horizontal rows, and the anchor blocks immediately adjacent to said buckstays being positively anchored thereto against lateral shifting and 95 tilting movements. 10

4. In a wall structure, the combination with upright buckstays, of horizontally disposed ledge plates secured to said buckstays, horizontal rows of sill blocks placed upon and interlocked to said ledge plates, and belts of brickwork filling the spaces between the horizontal rows of sill blocks. 10

5. In a wall structure, the combination with upright buckstays, of horizontally disposed ledge plates secured to said buckstays, horizontal rows of sill blocks placed upon and interlocked to said ledge plates, belts of brickwork filling the spaces between the horizontal rows of said sill blocks, and metallic anchors applied to the upper portions of certain of said sill blocks and interlocked with said buckstays. 11

6. The structure defined in claim 4 in which said ledge plates are detachably anchored to said buckstays and are positively held therewith in the complete wall. 12

7. In a wall structure, the combination with upright buckstays provided on their inner faces with anchor brackets with inwardly offset upwardly projecting portions, of metallic ledge plates having downturned outer edge flanges detachably interlocked to the buckstays by said anchor brackets, said ledge plates at their inner edges having up- 13

turned flanges, sill blocks seated on said ledge plates and having grooves with which the upturned inner edge flanges of said ledge plates are engaged, and horizontal belts of brickwork laid upon said sill blocks and filling the spaces between vertically spaced horizontal rows thereof.

8. The structure defined in claim 7 in further combination with metallic anchors detachably interlocked with the upper portions of certain of said sill blocks and themselves detachably anchored with said buckstays.

9. The structure defined in claim 7 in which said ledge plates are made up of sections, the abutting ends of which are lapped with the buckstays and with the flanges of said anchor brackets.

10. In a wall structure, the combination

with upright buckstays having anchor brackets, of metallic ledge plates having 20 downturned outer flanges detachably interlocked to the buckstays by said anchor brackets, said plates having at their inner edges upturned flanges, sill blocks seated on said ledge plates and having grooves engaged with the upturned flanges of said ledge plates, certain of the sill blocks being provided in their upper faces with T shaped grooves, and said metallic anchors being provided with T shaped portions 30 engaging the T shaped grooves, the outer ends of said anchors having offset hook-like portions detachably engaged with adjacent flanges of the buckstays.

In testimony whereof I affix my signature.
MICHAEL LIPTAK.
